DRIVING PAD RISER FOR DISC FLOOR SURFACING MACHINE

John R. Anderson, Maplewood, Minn., assignor to Minnesota Mining and Manufacturing Company, St. Paul, Minn., a corporation of Delaware

Filed Nov. 23, 1966, Ser. No. 4,792

Term of patent 14 years

(Cl. D37—1)

FIGURE 1 is a top plan view of the driving pad riser for disc floor surfacing machine, made in accordance with my invention;

FIGURE 2 is a bottom plan view;

FIGURE 3 is a front elevational view, the dashed lines indicating the association of the driving pad riser with additional elements, for illustrative purposes only.

FIGURE 4 is a cross-sectional view taken along the section line 4—4.

I claim:

The ornamental design for a driving pad riser for disc floor surfacing machine, substantially as shown and described.
